Primary Examiner — Anhdao Doan(74) *Attorney, Agent, or Firm* — David S. Bradin; Nexsen Pruet, PLLC**(57) CLAIM**

The ornamental design for a phototherapy cap, as shown and described.

DESCRIPTION

FIG. 1 is a right side elevational view of a phototherapy cap showing our new design;

FIG. 2 is a left side elevational view thereof;

FIG. 3 is a rear elevational view thereof;

FIG. 4 is a front elevational view thereof;

FIG. 5 is a top plan view thereof;

FIG. 6 is a bottom plan view thereof; and,

FIG. 7 is a perspective view thereof.

The broken lines in FIGS. 4, 6 and 7 illustrate portions of the phototherapy cap that form no part of the claimed design.

1 Claim, 7 Drawing Sheets(56)
